H. S. Chapin
ATTORNEY

UNITED STATES PATENT OFFICE.

HENRY S. CHAPIN, OF ROCKVILLE CENTER, NEW YORK.

WOODY PIPE FOR SMOKING TOBACCO.

1,099,965.

Specification of Letters Patent.

Patented June 16, 1914.

Application filed April 21, 1911. Serial No. 622,527.

To all whom it may concern:

Be it known that I, HENRY STERLING CHAPIN, a citizen of the United States, and resident of Rockville Center, in the county 5 of Nassau and State of New York, have invented certain new and useful Improvements in Wooden Pipes for Smoking Tobacco, of which the following is a specification.

10 My invention relates to the construction of a pipe and the art of manufacture. Pipes of wood such as briar and imitation are often colored, shellacked, varnished, oiled or otherwise treated in order to 15 prove their appearance for the purpose of display and sale. The first smoker of such a pipe gets the flavor of all the finishing materials on the interior of the pipe together with the effects of combustion of the interior 20 surface layer of wood. The flavor is sickening. The fact is, that many smokers judging from their first experience with a new pipe believe that they cannot smoke a pipe at all although from motives of economy and other attractive features of pipe smoking they would be very glad to adopt the use of a pipe.

It is my object therefore to so prepare an ordinary wooden pipe before selling the 25 same for use that it will be equally attractive from the standpoint of appearance and will smoke sweet the first time it is tried.

The improved form of pipe has a bowl of suitable wood which is scorched on the interior sufficiently to remove any natural or 30 artificial oils and resins and any coloring matter or other finishing material but without destroying the cellular structure of the outer part of the bowl or weakening it to 35 any substantial extent. The method employed in the preparation of the bowl is the use of an open flame or heated iron or other member. Preferably the scorching is limited to the bottom and sides of the bowl leaving a narrow rim around the upper edge of 40 the bowl unscorched. This accomplishes all that is necessary in the elimination of offensive taste-producing elements and still preserves the outward appearance of the bowl.

45 A seal, cap or other suitable form of closure may be employed to cover the bowl and indicate that it has been treated according to my invention and to prevent the entrance of foreign matter and the absorption of 50 gases by the prepared inner surface of the bowl.

Figure 1, is a side view of a pipe embodying the improvements of my invention, the bowl being shown in section. Fig. 2, is a perspective view of a pipe with a closure. Fig. 3, is a sectional view of a bowl of a pipe showing a heated mandrel for scorching the interior of the bowl. Fig. 4, is a similar view showing a flame from a torch for scorching the bowl and a collar for protecting the edge. Fig. 5, is a view showing a cap heated by an open flame for scorching the interior of a bowl.

The invention is applicable to any shape or style of wooden pipe and applies only to 70 the bowl. Any form or material of mouth-piece may be employed.

The bowl 1 is of any suitable wood. The inner surface 2 is scorched or partially burned so as to remove all natural or artificial matter from the wood which has offensive taste-producing qualities. The upper inner edge 3 is preferably left unscorched. This gives a good appearance and will not affect the smoking quality of the pipe since there is no combustion at the upper edge.

A seal 4 or other cap or closure is shown in Fig. 2 and it may be secured in place in any suitable manner.

In Fig. 3 the mandrel 5 is heated by a flame from a burner 6 and is of sufficient size to scorch the interior of the bowl when the pipe is relatively rotated on the mandrel.

In Fig. 4 the bowl is shown as being scorched on the interior by a flame from the torch 7. A ring 8 may be employed to prevent the scorching of the edge of the bowl.

In Fig. 5 the bowl is shown as being scorched by a cap 9 heated by a flame from a burner 10.

Any other suitable form of apparatus may be employed for carrying the invention into effect.

By my invention the taste of freshly burning wood and varnish, dyes, oils or other finishing materials commonly used by pipe makers is removed and the pipe is thus made more readily salable or salable at a higher price because pleasanter to smoke. This process also enables me to make attractive and good-smoking pipes even of cheap material.

When a wooden pipe is first smoked the pores of the wood absorb the nicotine from

the tobacco and the smoking flavor of the pipe is materially changed. In a pipe treated according to my invention however, the inner surface of the bowl is charred but remains absorptive and is free from nicotin as well as from other unpleasant taste producing substances.

What I claim is:—

1. As a new article of manufacture a new pipe bowl and stem formed of a single piece of natural wood and burned only on the inside of the bowl by suitable means substantially as described, the inner surface being thus charred and free from unpleasant taste producing elements, the remainder of said bowl and stem having the natural strength and absorptive properties of the wood, said bowl and stem being free from nicotin.
2. The art of forming a wooden pipe bowl which consists in shaping the bowl and stem in one piece and then burning only the interior of the bowl by suitable means substantially as described sufficiently to remove unpleasant taste producing elements from the inner surface and leaving the inner surface of the bowl absorbent and leaving the natural wood exposed and absorbent in the stem and without affecting the strength of the bowl or the stem and without adding nicotin.
3. The art of forming a wooden pipe

which consists in shaping the bowl and then burning the interior of the bowl sufficiently to remove unpleasant taste producing elements from the inner surface of the natural wood and without affecting the strength of the bowl and without adding nicotin.

4. The art of forming a wooden pipe which consists in first shaping the interior of the bowl, and then applying heat to the interior of the bowl and maintaining the heat substantially constant for a sufficient length of time to burn the interior of the bowl sufficiently to remove substantially all of the unpleasant taste producing elements from the inner wall of the bowl, but without materially affecting the strength of the bowl and without adding nicotin.

5. As a new article of manufacture, a new pipe bowl formed of natural wood with a charred inner wall formed by burning only the inside of the bowl by suitable means, the said bowl having substantially all the natural strength and absorptive properties of the wood, and the said inner wall being absorptive and free from nicotin and free from substantially all unpleasant taste producing elements.

HENRY S. CHAPIN.
